UNITED STATES PATENT OFFICE.

ISAAC OSGOOD, OF AMESBURY, MASSACHUSETTS.

DESIGN FOR A FRAME FOR TOWEL-RACKS.

SPECIFICATION forming part of Design No. 27,786, dated October 26, 1897.

Application filed August 11, 1897. Serial No. 647,925. Term of patent 14 years.

To all whom it may concern:

Be it known that I, ISAAC OSGOOD, a citizen of the United States, residing at Amesbury, in the county of Essex and State of Massachusetts, have invented a new and original Design for Towel-Racks, &c., of which the following is a specification, reference being had therein to the accompanying drawings.

In the said drawings, Figure 1 is a plan view of a plate or casting embodying my design. Fig. 2 is a view in section on line 2 2 of Fig. 1. Fig. 3 is a perspective of the said plate or casting.

As shown in the drawings, the leading or material features of my design comprise the essentially triangular shape of the plate or casting 1, the two forward edges 2 3 having

the rounded swells 4 4 and entrant angles 5 5 at the junctions of the said swells, the rounded apex 6 at the junction of the said forward edges, and the circles 7 7, concentric with the swells 4 4 and apex 6. The number of swells and circles may vary, being determined by the size of the casting or plate.

I claim as new and desire to secure by Letters Patent—

The design for a frame for towel-racks and the like, as herein shown and described.

In testimony whereof I affix my signature in presence of two witnesses.

ISAAC OSGOOD.
